UNITED STATES PATENT OFFICE.

MAX S. SHAPIRO, OF BROOKLYN, NEW YORK.

SIGNAL DEVICE FOR AUTOMOBILES.

1,405,165.

Specification of Letters Patent. Patented Jan. 31, 1922.

Application filed October 9, 1920. Serial No. 415,926.

To all whom it may concern:

Be it known that I, MAX S. SHAPIRO, a citizen of the United States, residing at 874 Eastern Parkway, borough of Brooklyn, 5 county of Kings, city and State of New York, have invented a certain new and useful Improvement in a Signal Device for Automobiles, of which the following is a specification.

10 My invention relates to a new and improved signaling device especially adapted for automobiles to indicate when the automobile is going to stop or turn.

15 Numerous accidents have been caused at the present time because of the fact that it is customary for such signals to be given by the driver stretching out one of his hands.

20 According to my invention a light and portable device is secured which is very compact when in the closed or inoperative position and in which the signal can be widely extended so as to give the proper warning.

25 Another object of my invention is to produce a device which will be very light and which can be operated by means of an electric current.

30 Other objects of my invention will be described in the following description and drawings which illustrate a preferred embodiment thereof.

Fig. 1 is a sectional view showing my device in the extended or operative position.

Fig. 2 is a top view of Fig. 1 and is partially in section.

Fig. 3 is a view similar to Fig. 1 showing the device in its inoperative or collapsed position.

40 Fig. 4 is a top view of Fig. 3. The device is mounted in a box or container 1 made of metal or other suitable material. It has at the bottom thereof an electro-magnet 2 of any suitable construction, the current to the coils thereof being supplied by the wires 3 which can be connected to any suitable source of electric current by means including a switch so that the circuit can be made and broken by the driver whenever desired. These details are not

45 50 illustrated in the drawings as in themselves they are old and well known. The armature for the electro-magnet 2 is pivoted at 5 and is normally held in the position shown in Fig. 3 by means of the spring 6. The

end of the armature 4 is provided with gear 55 teeth as shown in Figs. 1 and 2, and these gear teeth mesh with the upper gear 7 which is also in mesh with the lower gear 8. The gears 7 and 8 have pivot members 9 which are connected to the casing 1. 60

The pivot members 9 carry the rear rods 10 of a lazy-tongs structure, the said rods 10 being pivoted to each other at the points 11 as is well known in devices of this character and being also pivotally connected at 65 the points 12.

The lazy-tongs structure may be connected to the canvas signal hand 14 at the outermost pivoted point 15 and if desired may also be connected to the said hand at 70 the points 11.

75 The rod 16 which is connected to the end of the lazy-tongs structure is secured to the finger part of the signal hand at the point 17.

The signal hand 14 is made of canvas or other suitable flexible material and is rolled around the roller 18 which is urged by the spring 19 to normally revolve so as to keep the signal hand 14 within the casing 1 as 80 is shown in Fig. 3.

When, however, the electro-magnet 2 is energized and the armature is pulled down from the position shown in Fig. 3 to the position shown in Fig. 1, the upper gear 7 85 is revolved counter-clockwise and the lower gear 8 is revolved clockwise so as to throw the lazy-tongs structure forward and unroll the signal hand 14 from the roller against the force of the spring 19 and throw the 90 hand into the operative position illustrated in Fig. 1.

If desired, the signal casing may be provided with an electric bulb 20 and with a lens 21 so as to illuminate the license number 95 plate or the plate bearing the license number may be attached to the casing 1 in any suitable way and illuminated in any suitable way.

100 It is also obvious that the device may be mounted at any desired part of the automobile such as the mudguard, the wind shield, etc.

I have described a preferred embodiment 105 of my invention but it is clear that numerous changes and omissions may be made without departing from its spirit.

Thus while I have specifically described

the lazy-tongs structure, it is obvious that other devices adapted to be operated by the gear wheels could be substituted therefor.

I claim:—

- 5 1. In combination, a casing having an electro-magnet therein, an armature for the said electro-magnet located within the said casing, the said armature having a toothed face adapted to cause the operation of two
- 10 gear wheels, and a lazy tongs structure secured to a signal arm made of bendable material, said structure being connected with said gear wheels so that it is operated by the movement of the said gear wheels,
- 15 whereby the movement of the said armature in one direction causes the said signal arm to be extended out of the casing while its movement in the opposite direction causes it to be retracted within the said casing.
- 20 2. In a signal device, the combination of a casing, an electro-magnet located within the said casing, an armature therefor located within the said casing, means operative to force the said armature away from
- 25 the said electro-magnet, two intermeshing gear wheels, a lazy-tongs structure comprising pivoted bars, the rear bars thereof being operatively connected to the said gear

wheels so that their revolution moves the said lazy-tongs structure out of the said casing, a signal arm made of fabric and having its rear secured to a roller, a spring normally urging the said roller to retract the said signal arm into the said casing, and teeth located on the said armature and meshing with one of the said gear wheels, so that when the said electro-magnet is energized, it urges the said armature to operate the said gear wheels, and forces the said signal arm out of the casing.

3. In a signal device, the combination of a casing, intermeshing gear wheels mounted on pivot members connected to the said casing, a lazy-tongs structure comprising pivoted bars, the rear bars of said lazy-tongs structure being connected to the said pivot members so that the revolution of the said gear wheels extends or collapses the said lazy-tongs structure, a signal arm made of flexible material and connected to the said lazy-tongs structure so as to be operated by the movement thereof.

In testimony whereof I hereunto affix my signature.

MAX S. SHAPIRO.
